UNITED STATES PATENT OFFICE.

CLAUDE M. GARLAND, OF CHICAGO, ILLINOIS.

APPARATUS FOR COOKING COAL.

1,402,413.

Specification of Letters Patent.

Patented Jan. 3, 1922.

Application filed December 22, 1917. Serial No. 203,345.

To all whom it may concern:

Be it known that I, CLAUDE M. GARLAND, a citizen of the United States, residing at Chicago, in the county of Cook and State of Illinois, have invented new and useful Improvements in Apparatus for Coking Coals, of which the following is a specification.

My invention relates to coke ovens and has for its object the provision of improved means for coking fuels whereby the time of coking is greatly reduced, consequently the size of a plant for a given capacity and the amount of by-products recovered greatly increased over present practice.

Further objects and advantages of the invention will be set forth in the description that follows:

In the present by-product coke oven the fuel is commonly charged into long retorts of rectangular section placed horizontally. These retorts are commonly made from eighteen to twenty inches in width, six to eight feet in depth, and of varying length. The heat for coking the coal contained in the retort is usually supplied by burning a portion of the gas distilled from the coal in side flues of brick construction. A silica brick wall forms the retort in which the coal is contained and the gases for heating are burned in the flues and are separated from the coal by this silica brick wall.

The temperature in the flues is ordinarily around 2600° F. and the temperature of the wall varies between 1800 and 2400 degrees F. Under these conditions the time required for coking the fuel varies from fifteen to twenty-four hours. The cause for this excessive length of time in coking is due to the fact that in order to produce a coke of uniform structure it is necessary to crush the coal which results in a very large amount of fine material. Since each particle of coal charged is surrounded by a film of air and since this air is confined so that the circulation of the air is very difficult and since air is one of the best non-conducting mediums of heat so long as it is confined, the mass of coal in the retort forms a highly insulating medium which renders the progress of heat through the mass very slow.

Simmersbach found in a Koppers oven of 19 and $\frac{1}{2}$ inches mean width operating on twenty-nine hours coking time with a final maximum temperature of 1120 degrees centigrade, that the temperature in the middle of the oven one meter above the floor re-

mained about 10 degrees centigrade for two and one-half hours after charging; then rose to 100 degrees centigrade and remained at this temperature until thirteen hours after 60 charging. At twenty hours the temperature was only 410 degrees centigrade. (Journal A. S. M. E. June, 1917, p. 498.)

The above experiments confirm the applicant's statement relative to the insulating properties of a mass of finely divided coal. In actual practice the coal fuses at a temperature around 400 degrees centigrade and the fused mass boils around 450 degrees centigrade and may even be coked at this temperature. In order to obtain a quick coking time it is necessary in the ordinary retort to use temperatures up to 2400 degrees F. These temperatures are exceedingly disastrous to the tarry by-products, as thirteen gallons of tar per ton of coke is excellent practice in present day by-product ovens. By the inventor's method this tar is increased to from twenty to thirty gallons per ton and instead of containing sixty per cent pitch, contains from twenty-five to thirty per cent pitch, the remainder being light oils.

In the inventor's apparatus the heat is applied to the mass of coal by forcing 85 through the mass a non-oxidizing gas at a comparatively high temperature which serves as a heat carrying medium to the particles of coal. The temperature of this gas is ordinarily in the neighborhood of 90 1100 degrees F. but may drop as low as 800 degrees and rise as high as 1500 degrees F. under special conditions. The gas used may be a part of the coke oven gas distilled from the coal which has been super-heated 95 but super-heated steam is preferably used as the heat carrying medium.

As this gas is forced through the finely divided coal the air particles are driven out and the mass of coal is rapidly brought 100 to the fusion temperature. The time required will depend upon the coarseness of the material, the weight of gas circulated and the temperature of the gas. It is entirely possible to fuse the mass in thirty 105 minutes time although this is working rather fast for practical operation. Fusion in one to two hours with complete coking in from three to six hours would represent working practice.

With some coals in which the amount of bituminous matter is not excessive the gas

may be passed through the mass during the entire coking period and in such cases coking is very rapid. Where there is a large amount of bituminous matter in the coal 5 the fluidity of the mass on fusion makes it difficult to force the gas through the mass after fusion.

Also with some coals the forcing of the gas through the mass until coking is completed 10 results in a coke of porous structure which is not desirable for commercial purposes. Provision is therefore made for surrounding the mass with the heated gas or superheated steam from the time the 15 fusion is completed until the end of the coking time. Even under these conditions coke may be formed in five or six hours' time due to the fact partly that the fused mass conducts heat much more readily after fusion 20 but largely due to the fact that after the coal is heated above the fusion point. The fact remains, however, that the coal cokes almost as rapidly after the passage of the heating medium is stopped as it does when 25 the passage of the heating medium through the coal is continued. The resulting coke, however, after stopping the passage of the heating medium, becomes much more dense.

There is also another advantage in the 30 method and that is due to sweeping out the air particles from the coal thereby removing the oxygen which in ordinary practice remains and unites with the volatile matter to produce carbon dioxide which destroys 35 a small amount of by-products and tends to prevent coking. In poorly coking coals the presence of this small amount of oxygen may seriously interfere with the coking operation.

40 Again due to the comparatively low temperatures required in the apparatus the retorts may be constructed of cast iron and thereby made absolutely tight thus preventing losses due to combustion which can not 45 be avoided in ovens constructed from brick work which is always porous.

The accompanying drawing which forms 50 a part of this specification illustrates more fully my invention. Referring to this drawing in which like numerals designate like parts in the various figures—Figure 1 shows an elevation in part section taken on the line YY of Figure 2. Figure 2 shows a plan in part section taken on the line XX 55 of Figure 1.

Referring to the figures the numeral 1 indicates a heating chamber which is formed by the walls 2 which are preferably made of cast iron. This chamber is 60 rounded by an insulating covering 3 and the whole is mounted on the beams 15 in any convenient manner. 4 indicates the retorts for holding the fuel which are preferably made with vertical side walls as shown. 65 These retorts are formed by the partitions

5 which are riveted into the walls 2 of chamber 1 and extend entirely across this chamber from top to bottom dividing the chamber into alternate retorts and gas compartments. A gas compartment is provided 70 between each retort and between each end retort and the end of the heating chamber. One or more retorts may be built into a heating chamber. These walls are provided with perforations 6 which are uniformly 75 spaced so as to distribute the heating medium through the material to be coked. These perforations may be of any convenient form to pass the heating medium. The tops of the retorts 4 are covered by cover 80 plates 7 and the bottoms by cover plates 8 which are held down by the links 9 and the screws 10. These tops are readily removable by backing off the screws 10.

The numeral 14 indicates a gas inlet 85 through which heated gas may be delivered to the heating chamber in the first compartment. 13 indicates a gas outlet from the heating chamber in the last compartment. 11 indicate pipes which establish communication 90 between the top of one compartment and the bottom of the next compartment. 12 is a valve for cutting off communication between each of the compartments, 16, located between the retorts 4.

The operation of the apparatus is as follows:—The bottom covers 8 are placed in position and forced up against the bottom of the retort by the screws 10. Coal is then charged into the retorts 4 and the top cover plates 7 fastened down. Superheated steam under a pressure of one or two pounds is then blown into the first compartment 100 through the gas inlet 14. This steam passes through the perforations 6 in the sides 5 of the retorts 4, through the coal contained therein and passes off through the gas outlet 13 together with the gases and tarry vapors distilled from the coal. If the coal is low in bituminous matter this steam is 105 blown through until coking is completed.

However, if there is a large amount of bituminous matter the steam is blown through until the mass of coal has fused. The valves 12 are then opened so that the steam and gases distilled from the coal pass from the bottom of the first compartment to the top of this compartment then through the pipe 11 to the bottom of the next compartment to the top of this compartment and then 110 through the pipe 11 to the bottom of the next compartment and so on until they pass out through the gas outlet 13. During this stage after fusion the gases simply circulate through the compartment 16 of the heating chamber 1, thus enveloping the mass of coking coal instead of passing through. After the mass has solidified and before the volatile matter is all distilled off the coking 115 may be hastened by closing the valves 12 120 125 130

thereby forcing the steam and gases again through the mass of partially coked fuel contained in the retorts 4.

After coking is completed the steam is shut off from the inlet 14, the top and bottom plates 7 and 8 removed and the mass of coke drops out as the retorts are given a slight taper so that they are larger at the bottom than at the top.

10 From the foregoing description it will be seen that simple and efficient means are herein provided for accomplishing the objects of the invention, but while the elements shown and described are well adapted to 15 serve the purposes for which they are intended it is to be understood that the invention is not limited to the precise construction set forth. The retorts for example may instead of being charged at the top and 20 charged at the bottom be charged at the top and discharged at the ends by means of horizontal pushers, the same as are used in high temperature by-product coke over practice. One retort may be placed in a heating 25 chamber instead of a number of retorts as shown by the drawings. The gases for carrying the heat may be circulated from top to bottom or from bottom to top. The invention could be applied to the present form 30 of coke oven retorts without serious alteration by forcing the heat carrying gases up through the porous bottom of the retort. It will, therefore, be understood that the foregoing description includes within its pur- 35 view such changes as may be made within the scope of the appended claims.

What I claim is—

1. The process of coking coal consisting in causing super-heated steam to pass through 40 the coal until fusion of the coal occurs, of stopping the passage of steam on the completion of fusion and of then enveloping the fused coal with the said super-heated steam until the coking is completed.

45 2. The process of coking coal consisting in causing a non-oxidizing gas near a temperature of 1,000° F. to pass through the coal until fusion occurs, of stopping the passage of the said non-oxidizing gas on the completion 50 of the fusion and of then enveloping the fused material with the said non-oxidizing gas until the coking is completed.

55 3. The process of coking coal consisting in causing a heating medium to flow through the said coal to be coked for a pre-determined time, of then stopping the flow of the said heating medium through the said coal and of completing the coking operation by surrounding the said coal with the said heating medium.

60 4. The process of coking coal consisting in starting the coking operation by causing a gaseous heating medium to flow through the said coal for a pre-determined time, depending upon the nature of the coal, of stopping

the flow of the said heating medium at the end of the said pre-determined time, and of then completing the coking operation by surrounding the coal with the said heating medium.

70 5. The process of coking coal consisting in starting the coking operation by heating the said coal contained in a retort internally by causing a heating medium to pass therethrough for a pre-determined time, of then 75 stopping at the end of the said pre-determined time the passage of the said heating medium, and of completing the coking operation by supplying heat externally to the sides of the said retort.

80 6. The process of coking coal, consisting in starting the coking operation by causing superheated steam at a temperature near 1,000° F. to pass through coal contained in a retort for a pre-determined time, depending 85 upon the nature of the coal, of then stopping the passage of the said superheated steam, and of completing the coking operation by causing the said superheated steam to circulate around the said retort.

80 7. The process of coking coal consisting in charging the said coal to a retort, of causing a heating medium to flow through the said coal contained in the said retort for a pre-determined time, of then stopping the 95 flow of the said heating medium, and of heating the said retort externally until the coking operation is completed.

8. In coking apparatus of the type described, a heating chamber, a plurality of 100 perforated partitions dividing the said chamber into alternate retorts and compartments, an inlet for the admission of a heating medium in one end compartment, an outlet for the discharge of the heating medium 105 in the opposite end compartment, a pipe establishing communication between each compartment and the next following compartment, and a valve in each of the pipes whereby communication between the said 110 compartments may be closed.

9. In coking apparatus of the type described, a heating chamber, a plurality of perforated walled retorts within the said chamber, a compartment for the circulation 115 of a heating medium between each retort and between the end retorts and the ends of the heating chamber, a removable cover for the top of each of the said retorts, and a removable cover for the bottom of each of 120 the said retorts.

10. In coking apparatus of the type described, a heating chamber, a vertical retort within the said heating chamber, a perforated vertical diaphragm forming one wall 125 of the said retort and partitioning off one end of the said heating chamber an inlet connection adapted to deliver superheated steam between the said perforated diaphragm and the end of the said heating 130

chamber, a second perforated diaphragm forming the opposite wall of the said retort and partitioning off the opposite end of the said heating chamber, and an outlet connection in the said opposite end of the said heating chamber whereby superheated steam may be caused to flow from the said inlet connection through the said retort, and the coal contained therein to the said outlet connection substantially as described.

11. In coking apparatus of the type described, a heating chamber, a retort within the said heating chamber, a perforated vertical diaphragm forming one wall of the said retort and partitioning off one end of the said heating chamber, an inlet connection adapted to deliver superheated steam between the said perforated vertical diaphragm and the end of the said heating chamber, a second perforated vertical diaphragm partitioning off the opposite end of the said heating chamber and forming the other wall of the said retort, and an outlet connection to the said heating chamber so disposed with relation to the said inlet connection that the superheated steam is caused to flow from the said inlet connection through the said perforated vertical diaphragms and the coal contained in the said retort to the said outlet connection.

12. In coking apparatus of the type described, a heating chamber, a retort within the said heating chamber, a perforated vertical diaphragm forming one wall of the said retort and partitioning off one end of the said heating chamber, an inlet connection adapted to deliver superheated steam between the said perforated vertical diaphragm and the end of the said heating chamber, a second perforated diaphragm forming the opposite wall of the said retort and partitioning off the opposite end of the said heating chamber, an outlet connection in the said opposite end of the said heating chamber whereby superheated steam may be caused to flow from the said inlet connection through the said retort, and the coal contained therein, to the said outlet connection, a pipe communicating with the said heating chamber on opposite sides of the said retort whereby steam may be caused to circulate around the said retort, and a valve for closing the said pipe.

13. In coking apparatus of the type described, a heating chamber, a retort contained in the said heating chamber, means whereby a heating medium may be caused to pass through the said retort and the material contained therein, and means for bypassing the said retort whereby the heating medium may be caused to surround the said retort.

14. In coking apparatus of the type described, a heating chamber, a retort extending through the said heating chamber, means

for causing a heating medium to flow through the said retort and the material contained therein, whereby the coking operation may be carried to any pre-determined point, and means for bypassing the said retort whereby the heating medium is caused to surround the said retort and the coking operation is completed by heating the said retort externally.

15. In coking apparatus of the type described, a heating chamber, a vertical walled retort extending through the said heating chamber, means for charging coal to the said vertical walled retort, a plurality of perforations distributed in the vertical walls of the said retort whereby a heating may be caused to flow uniformly through the said retort and the coal contained therein, means for causing a heating medium to flow from one end of the said heating chamber through the said perforations in the vertical walls of the said retort and through the material contained therein to the opposite end of the said heating chamber, and means for discharging the resulting coke from the said retort.

16. In coking apparatus of the type described, a heating chamber, a vertical walled retort extending through the said heating chamber, means for charging coal to the said vertical walled retort, a plurality of uniformly distributed perforations through the walls of the said retort, means for supplying a heating medium at one end of the said heating chamber whereby the said heating medium is caused to pass through the said uniformly distributed perforations in the said vertical walls of the said retort through the material contained in the said retort to the opposite end of the said heating chamber, communicating means between the two ends of the said heating chamber whereby the said heating medium may be caused to surround the said retort, and means for discharging the coke formed.

17. In coking apparatus of the type described, a heating chamber, a plurality of vertical partitions extending across the said heating chamber whereby the said heating chamber is divided into a plurality of vertical walled retorts and gas compartments, each retort being separated from the next retort and the end retorts being separated from the ends of the said heating chamber by a gas compartment, a plurality of perforations in the said vertical partitions whereby a heating medium may be caused to pass uniformly through the said retorts and the material contained therein, an opening for the admission of a heating medium in the gas compartment at one end of the heating chamber, an opening for the discharge of the said heating medium and the gas distilled from the material within the said retorts in the gas compartment.

- partment at the opposite end of the said heating chamber whereby a heating medium may be caused to flow from the gas compartment at one end of the said retort through 5 the said vertical partitions and the material contained therebetween.
18. In coking apparatus of the type described, a heating chamber, a plurality of vertical partitions extending across the said heating chamber whereby the said heating chamber is divided into alternate vertical 45 walled retorts and gas compartments, a gas compartment being formed in each end of the said heating chamber and between each of the said retorts, a plurality of uniformly spaced perforations in the said vertical partitions, means for causing a heating medium to flow from the gas compartment in one end of the heating chamber through the said vertical walled retorts and the material contained therein, means for charging coal to the said retorts and means for discharging the coke formed therein. 50
19. In coking apparatus of the type described, a heating chamber, a plurality of vertical partitions extending across the said heating chamber whereby the said heating chamber is divided into alternate vertical walled retorts and gas compartments, a gas compartment being formed in each end of the said heating chamber and between each 55 of the said retorts, a plurality of uniformly spaced perforations in the said vertical partitions, a pipe for the admission of a heating medium communicating with the gas compartment in one end of the said heating chamber, a pipe for the discharge of the said heating medium communicating with the gas compartment in the opposite end of the said heating chamber, a pipe establishing communication between each gas compartment and the following gas compartment, and a valve for closing each of the said pipes whereby at will a heating medium may be caused to flow from the gas compartment at one end of the said heating chamber through the said uniformly 60 spaced perforations in the said vertical partitions and the material contained therebetween to the outlet pipe communicating with the gas compartment at the opposite end of the said heating chamber or whereby a said heating medium may be caused to circulate from the gas compartment in one end of the heating chamber through each of the other said gas compartments to the said pipe in the gas compartment in the opposite end of 65 the said heating chamber.
20. In coking apparatus of the type de- 70
- scribed, a heating chamber, a plurality of vertical partitions extending across the said heating chamber whereby the said heating chamber is divided into alternate vertical walled retorts and gas compartments, a gas compartment being formed in each end of the said heating chamber and between each of the said retorts, a plurality of perforations in each of the said partitions, means for causing a heating medium to flow at will either from the compartment in one end of the said heating chamber through the perforations in the vertical walled retorts to the gas compartment in the opposite end of the said heating chamber, or, for causing the heating medium to flow from the first named gas compartment around each of the said retorts to the last named gas compartment, means for charging coal to the said retorts and means for discharging the coke formed therein substantially as described. 75
